WEBSTER TALLMADGE, OF MONTCLAIR, NEW JERSEY, ASSIGNOR TO WEBSTER TALLMADGE & COMPANY, INC., OF NEW YORK, N. Y., A CORPORATION OF NEW YORK.

FLUID-CIRCULATING SYSTEM.

Application filed November 8, 1924. Serial No. 743,691.

This invention relates to a fluid circulating system, and, specifically, to a steam heating system, for a single building or for a group of buildings, although not limited thereto since, as will be apparent, it is applicable either in whole or in part for other uses.

In the heating of buildings the steam, generated in the basement of the building itself or of an adjacent building or supplied at high pressure from some central station, is admitted through a valve to a low pressure main and from such main is distributed through risers, in a large building usually one or more on each of its sides, to radiators located one above another on the different floors.

The amount of steam required to heat a given area depends largely of course upon the outside temperature, which varies not only according to the latitude and season but also from day to day and, daily, from night to day. It further varies widely, on different sides of a building, according to the direction and velocity of the wind and whether or not the rooms are exposed to the sun. Hence, in order to adequately and comfortably heat a given area, it is necessary not only to keep the total supply of steam constantly adjusted to the amount required for the entire area served but also to regulate from time to time its distribution through the different risers according to the ever varying conditions of sun and wind; otherwise, the rooms on one front will be insufficiently heated while those facing in another direction will be overheated, thus causing discomfort to the occupants and a waste of steam.

Numerous methods have been employed for controlling the supply of the steam, openings of different sizes have been used to more or less permanently secure a constant distribution of the steam to the different risers and, perhaps, to the individual radiators, and automatic means responsive to temperature have been used for controlling the admission of steam to each radiator. But these methods are all objectionable. The fixed openings to the risers make no provision for changeable conditions. And thermostatic control is not only expensive and difficult to maintain in satisfactory operation but is also uneconomical—for instance, if the occupant of a sun-lighted room

opens the window to let in fresh air and to cool off the thermostat responds by admitting more steam to the radiators.

The object of the present invention is to provide a heating system wherein both the supply of steam and the distribution thereof to every part of a building or group of buildings, large or small, may be quickly, accurately and intelligently controlled by an engineer or other attendant from some conveniently located central point, however remote, thereby making possible the comfort of all the occupants with the use of a minimum amount of steam.

To this end my improved system comprises, as one of its features, a motor-operated valve which controls the admission of the steam from the supply pipe to the low pressure distributing main, preferably through an intermediate pressure chamber or passage interposed between the valve and the main, and which in turn is controlled by automatic means responsive to the volume of steam passing through the valve for starting in either direction and for stopping the valve motor; and, in addition, means whereby the attendant, from some convenient station, may adjust such pressure responsive means so that they will automatically maintain the valve in a position to permit the passage of steam in the volume desired.

As a further feature, my new system comprises means for controlling the distribution of the steam from the low pressure main to the different risers which may be, and preferably are, controlled by the attendant from the single central station. The control may be carried a step further, if desired, by employing the same or similar means for regulating the distribution of the steam from the risers to the several radiators connected therewith.

The invention also includes the other novel features and combinations of features hereinafter described and more particularly pointed out in the appended claims.

In the accompanying drawings Figure 1 shows diagrammatically, by way of illustration and not of limitation, one specific embodiment of the several features of the invention in connection with so much of a heating system as is necessary for the understanding of the operation thereof, Fig. 2 is an enlarged detail illustrating a modification, and Figs. 3 and 4 are views, in side ele-

vation with parts in section and in section on the line 4—4 of Fig. 3, respectively, of a polarized selector relay.

As here illustrated, the heating system proper comprises the supply pipe 1, supplied with steam at high pressure, a low pressure main 6 to which steam is admitted from the supply pipe, under the control of the valve 2, through a diffuser 5 equipped with a pressure nozzle 4, and a series of risers 7 8 9 10, provided with control valves or dampers 11 12 13 14, respectively, which are located, for example, one on each side of the building to be heated and which carry the steam from the main to the radiators (not shown). The pressure nozzle 4 serves to build up and to maintain in the passage or chamber between it and the valve a pressure, dependent upon the flow of steam therethrough, which is intermediate that in the supply pipe and that in the main and which is utilized, as will be seen, for the control of the steam supplied to the system.

The control valve 2 is operated by an electric motor 3, here shown as a series field direct-current motor, which is provided with operating circuit connections comprising the wires *a b* (connected by a switch to suitable mains) *c d e f* and *g*. These motor circuits, both armature and field, are controlled by relays 15 16 17 and 18 the actuating circuits of which, comprising the wires *h h¹ i i¹* and *j*, are in turn controlled by two spring contact fingers 19 and 20 normally held in open position but adapted to be pressed to one side, 19, against a fixed contact electrically connected with the wire *h* and 20 against a fixed contact electrically connected with the wire *h¹*. The spring contact fingers are actuated or controlled, automatically, by the pressure in the intermediate pressure chamber on the discharge side of the valve 2 by means of a pressure responsive device comprising a bourdon tube 21, which at its fixed end is connected with the pressure chamber by a pipe 22, and a floating lever 24 which at one end has a lost-motion connection with a link 23 pivoted to the free end of the bourdon tube, which is supported by a flanged roller 25 riding upon the cam 26 and held in contact therewith by a spring 27, and which at its outer free end carries a button 28, of insulating material, located between and in operative relationship with the two spring contact fingers. The cam 26, which is pivotally mounted, is rotated in either direction, to the desired position, by a polarized selector relay 29—by means of a double reverse pawl and ratchet or other suitable connection of its armature with the cam—the coils of which are connected with suitable mains through a motor-driven current interrupter 30, by wires *k l m n o p*, controlled by a reversing or polarity changing switch 31. A second polarized selector

relay 29^a, with its coil inserted in the wire *n* and hence in series with the coil of relay 29, has its armature operatively connected in a similar manner with a pivotally mounted indicator disk 26^a, corresponding to the cam 26. The switch 31 and the relay 29^a and its indicator disk are preferably mounted upon a panel or switch-board which may be located at any point convenient for the attendant in charge of the plant. 75

A selector relay suitable for the purposes of my invention—the relay 29 for example—is shown in Figs. 3 and 4. This relay is provided with a permanent magnet 50, which is to be secured in position in any suitable manner and in which is journaled a shaft 51 carrying, fixed to one end (here broken away), the cam 26 for example. Mounted adjacent the ends of the two legs or poles of the magnet and constituting extensions thereof are two armatures 52 52^a which are pivoted upon a rod 53 fixed in side plates 54 54^a attached to the legs of the magnet 50 and are connected together at their outer free ends by a narrow bar 55; and secured to the enlarged outer ends of the side plates 54 54^a respectively, are two electromagnets 56 56^a the cores of which are bent around and inwardly so that their poles 57 57^a and 58 58^a will adjoin the opposite sides of the respective armatures. The coils of the two electro-magnets are reversely wound and are connected together in series, in the circuit of the wires *m n* for example. The shaft 51 carries loosely mounted thereon, between the legs of the magnet 50 and separated therefrom by tubular spacers, the reversed ratchet-wheels 60 60^a which are operatively connected together and to the shaft by a differential comprising the bevel-gears 61 61^a fixed to the ratchet-wheels 60 60^a respectively and a third bevel-gear 62 meshing with the gears 61 61^a and rotatably mounted upon a pin 63 set in a spacing block fixed to the shaft. The ratchet-wheel 50, held against rotation in one direction by a spring stop 64 mounted on a bracket 65 secured to the legs of the magnet 50, is rotated clockwise (as seen, in Fig. 4) by a spring pawl 66 carried by the arm 67 which arm 115 is connected with the stop 64 by a spring 68 and limited in its movement towards said stop by a screw 69 adjustably mounted in the bracket 65, is pivoted on the rod 53 between tubular spacers, and has an extension 120 70 held in engagement with one side of the bar 57 by the spring 68. Similarly, the ratchet-wheel 60^a, provided with a spring stop 64^a mounted on the bracket 65^a, is rotated counter-clockwise by a spring pawl 66^a 125 carried by the arm 67^a which arm is connected with the stop 64^a by a spring 68^a and is limited in its movement towards said stop by the screw 69^a adjustably mounted in the bracket 65^a, is pivoted on the rod 53 between 130

tubular spacers, and has an extension 70^a held in engagement with the opposite side of the bar 57 by the spring 68^a. It is apparent that the armatures 52 52^a, forming parts of the magnetic circuit of the magnet 50, will be permanently magnetized, one—52 for example—positively and the other negatively. Thus, when an intermittent current is sent over the wires *m n* in one direction the poles 10 of the electromagnets will alternately be magnetized, 57 negatively and 58 positively to attract and 57^a positively and 58^a negatively to repel the two armatures thereby rocking the arm 67 and drawing the pawl 15 66 back one tooth on the ratchet-wheel 60, and demagnetized, to release the armatures and allow the spring 68 to rotate the ratchet-wheel and through it the shaft one step and at the same time to restore the armatures to 20 their normal central position. And similarly, when the current through the coils of the electromagnet is reversed, the ratchet-wheel 60^a and through it the shaft will be rotated counter-clockwise step by step.

25 The operation of the system so far as hereinabove described is as follows: Whenever the switch connecting the circuit wires *a* and *b* with the mains is closed, the valve will, through the operation of the pressure responsive device and the relays controlling the circuits of the valve motor, automatically be brought to a position to admit a flow of steam from the supply pipe which will produce and maintain at the nozzle 4 a constant pressure of a value dependent upon the position of the cam 26 upon which the floating lever 24 is fulcrumed. For example, if the valve is closed or is not open far enough to permit a flow of steam sufficient to create 35 the pressure for which the device is adjusted, the bourdon tube will cause the link 23 to drop somewhat and so permit the spring to rock the floating lever and thereby raise the button at its outer end and press the spring contact finger 19 against the fixed contact of wire *h*. Thereupon, circuit wires *h* and *i* being connected, current will flow by these wires through the coils of relays 15 and 17 and back by wire *j* to the other side of the line, these two relays will be actuated and, closing their contacts, will close the circuits of the valve motor—current passing by wires *a* and *c* through the series field of the motor and by wire *d*, contacts of relay 17 and wire 40 *e* through the armature of the motor and thence by wire *f*, contacts of relay 15 and wires *g* and *b* back to the other side of the line—starting the motor in a direction to open the valve. And as the increased flow 45 of steam through the valve builds up the pressure in the intermediate pressure chamber, the bourdon tube will straighten out and rock the floating lever so as to remove the pressure of its button from the contact finger, which thereupon will spring back to 50 open position and so break the circuits of the two relays and through them the circuits of the motor. If, on the other hand, the valve is opened too wide, the pressure created and communicated to the bourdon tube will 55 straighten out the tube and thereby rock the floating lever to a position which will press the spring contact finger 20 against its co-operating fixed contact. Wire *h*^a and *i*^a being then connected, current will flow through the coils of relays 16 and 18, which on closing will close the circuits of and so start the motor; but in this case the armature current, passing from wire *d* over the contacts of relay 15 and by wire *f* through the armature 60 and back to the line by wire *e*, will be reversed and consequently the motor will be operated in a direction to close down the valve. As soon as the flow of steam and hence the pressure have been reduced to the 65 value predetermined by the adjustment of the cam fulcrum of the floating lever, the free end of the bourdon tube will drop and the spring will rock the lever to thereby allow the contact finger to open contact and 70 so stop the motor. Whenever, due to changing conditions, the supply of steam thus automatically determined by the adjustment of the cam 26 becomes either excessive or inadequate, the attendant, at his switchboard, can at once change such adjustment by a simple manipulation of the polarity changing switch 31. Thus, by throwing the central movable contacts of this switch to 75 one side, against the upper fixed contacts for instance, the current impulses produced by the interrupter will be transmitted by wires *k l* and *m* to the coils of relay 29 and thence back by wire *n*, through the coils of relay 29^a, and wires *o* and *p*, and the 80 armatures of both relays, which with each impulse of current will be attracted to and released from the right hand poles of the selector relays, will act through one of the two pawl and ratchet sets to simultaneously 85 rotate tooth by tooth both the cam 26 and the indicator disk 26^a in a counter-clockwise direction. Such rotation of the cam, by lowering the point of support of the floating lever, renders the pressure responsive device operative at lower pressures, with the 90 result that the valve will be automatically shifted in the manner described to a position corresponding thereto. As soon as the indicator disk shows that the cam has been 95 moved sufficiently to effect the adjustment desired, the switch is thrown open and the movement of the cam instantly arrested. Similarly, to adjust the device to a higher 100 pressure, to thereby secure an increased flow of steam through the valve, the movable contacts of the switch 31 are thrown to the other side and held against the lower fixed contacts until, the current impulses passing through the coils of the relays in the reverse 105 direction, the cam is rotated in the 110 115 120 125 130 direction to increase the pressure.

direction and by the alternate attraction and release of the armatures to and from the left hand poles causing a clockwise movement of both indicator disk and cam, the 5 disk shows that the desired adjustment of the cam has been secured.

The means here employed to control the distribution of steam from the main to the several risers are the same as those used for 10 the adjustment of the pressure responsive device which controls the steam supply. To the stems of the valves 11 12 13 14 are respectively attached gears 11^a 12^a 13^a 14^a and in mesh with these gears are pinions 35 37 15 39 41, which are operatively connected with and are rotated in either direction by the armatures of the polarized selector relays 36 38 40 42. The circuit connections of 20 these relays, which are substantially the same as those of the cam-actuating relay 29 already described and also include the coils of duplicate selector relays 36^a 38^a 40^a 25 42^a in series each with the coil of one of the main selector relays and respectively actuating the indicator disks 35^a 37^a 39^a 41^a, are 30 similarly controlled through the current interrupter by the polarity changing or reversing switches 46 47 48 49 respectively. The duplicate selector relays, indicator disks and 35 switches may be, and preferably are, mounted upon the same panel which carries the selector relay 29^a, indicator disk 26^a and switch 31.

Assuming that the riser 7 is located on 35 the north side of a building and that a cold north wind is blowing while riser 9 is on the south side which is cut off from the wind and is exposed to the sun, it is obvious that the radiators supplied by the former will 40 require much more steam than those supplied by the latter. Accordingly, the attendant will throw the movable contacts of switch 46 up against its upper fixed contacts and hold them there until, the current 45 impulses passing by wires *h* *g* and *r* to the coil of relay 36 and thence back by wire *s*, coils of relay 36^a and wires *t* and *p* and thereby producing a counter-clockwise rotation of pinion 35 and a clockwise rotation of 50 gear 11^a, the indicator disk 35^a, rotating counter-clockwise, shows that the valve 11 has been sufficiently opened; and will also throw switch 48 down to connect its lower contacts with the line for the length of time 55 required for the current impulses, by wires *h* *q*² and (through the coils of relay 40^a) *s*² to the coil of relay 40 and back therefrom by wires *r*² *t*² and *p*, to effect a closure of the valve 13 to the extent desired, as indicated 60 by the disk 39^a. The valves in the other risers are similarly adjusted by the manipulation of switches 47 and 49.

In case the system is supplied with steam or other fluid at a constant pressure, it may 65 be found desirable to use the selector relay

to control the circuits of the valve motor directly, without the intervention of a bourdon tube. The modification illustrated in Fig. 2 is adapted for this purpose. Here, the spring contact fingers 19^x 20^x and the 70 fixed contacts at the ends of the wires *h* *h*¹ are carried by the arm of a rack-bar 24^x which is reciprocated up and down by a pinion 26^x, substituted for the cam 26 and similarly actuated by the selector relay 29, 75 while the button 28^x of insulating material is mounted upon the reciprocating stem 2^x of the valve 2. Thus, by manipulating the switch 31 the attendant can start the valve motor in either direction and thereby open 80 or close the valve by stages to any desired extent.

Thus, as is seen, my new system provides the means whereby a single attendant is able, from some convenient central point 85 however remote to quickly, intelligently and effectively regulate and control both the supply and the distribution of a fluid, like steam, over an extended area, thereby among its manifold advantages, making 90 possible a saving in time, an economical use of the fluid, and, in the case of a steam heating plant, the maximum comfort of all the occupants of the building or buildings 95 served thereby.

It is to be understood that for the specific control means illustrated and described equivalent means may be substituted. For example, the relays may be reorganized for use with alternating currents or for wire- 100 less operation; and duplex three-wire reversible selectors may be used in place of the polarized selector relays. Other obvious changes in the various details of the system—for instance, a reversal of the 105 mounting of the spring contact fingers and of the insulated button—may be made without departing from the spirit or sacrificing the substantial advantages of the invention.

What I claim as new, and desire to secure 110 by Letters Patent, is:—

1. A fluid circulating system comprising a source of fluid supply, a circulating main, means for controlling the flow of the fluid from the supply source to the main, electrical means for actuating the fluid flow control means, and means responsive to pressure created by such flow for controlling said electrical actuating means. 115

2. A fluid circulating system comprising a 120 source of fluid supply, a circulating main, means for controlling the flow of the fluid from the supply source to the main, electrical means for actuating the fluid flow control means, and means responsive to selectively different pressures created by such fluid flow for controlling said electrical actuating means. 125

3. A fluid circulating system comprising a 130 source of fluid supply at high pressure, a

- relatively low pressure circulating main, means for controlling the flow of fluid from the high pressure supply to the main, means responsive to pressure created by the flow of fluid from the high pressure supply for controlling said control means, and electrically actuated means for adjusting said pressure responsive means so as to respond to different values thereof.
10. 4. A fluid circulating system comprising a high pressure supply pipe, a low pressure circulating main, a power operated valve controlling the admission of fluid from the supply pipe to the main, a passage intermediate the valve and the main adapted to maintain therein an intermediate pressure dependent upon the volume of the fluid passing through the valve, and means responsive to pressure in such intermediate pressure 15 passage for controlling the valve operating mechanism.
5. A fluid circulating system comprising a high pressure supply pipe, a low pressure circulating main, a power operated valve controlling the admission of fluid from the supply pipe to the main, a passage intermediate the valve and the main adapted to maintain therein an intermediate pressure dependent upon the volume of the fluid passing 20 through the valve, means responsive to the pressure in such intermediate pressure chamber for controlling the valve operating mechanism, and electrically actuated means for controlling the pressure responsive means 25 so as to render the same responsive to different pressures.
6. A fluid circulating system comprising a high pressure supply pipe, a low pressure main, a valve controlling the admission of fluid from the supply pipe to the main, an electric motor operatively connected with the valve, circuit connections for the motor, and means responsive to the volume of fluid passing 30 through the valve for controlling the 35 circuits of the motor and adapted on an increase of the fluid flow above a predetermined value to close the motor circuits so as to start the motor in a direction to close the valve and on a decrease of the fluid flow 40 to close the motor circuits so as to start the motor in a reverse direction to open the valve.
7. A fluid circulating system comprising a high pressure supply pipe, a low pressure main, a valve controlling the admission of fluid from the supply pipe to the main, an electric motor operatively connected with the valve, circuit connections for the motor, and means responsive to the volume of fluid passing 45 through the valve for controlling the circuits of the motor which are adapted on an increase of the fluid flow above a predetermined value to close the motor circuits so as to operate the motor in a direction to 50 close the valve and on a decrease of the fluid flow to close the motor circuits so as to start the motor in a reverse direction, and means controllable from a distance for rendering the motor circuit control means responsive to varying values of the fluid flow.
8. A fluid circulating system comprising a high pressure supply pipe, a low pressure main, a valve controlling the admission of fluid from the supply pipe to the main, an electric motor operatively connected with the valve, circuit connections for the motor, and means for controlling the motor circuit which include an electric switch and a switch actuating member one of which is movably mounted and electromagnetically actuated means for adjustably shifting the movable element to and from the other element to thereby control the actuation of the switch.
9. In a fluid circulating system, the combination of a valve for the admission of the fluid thereto, an electric motor operatively connected with the valve, circuit connections for the motor whereby it can be operated in either direction, and control means for the motor circuits which include two electric switches, a member adapted on a change in the relative positions thereof to effect the actuation of either switch, and a selector relay whereby to effect step by step a determinate change in the relative positions of said member and either switch to thereby control the actuation of such switch.
10. In a fluid circulating system, the combination, with a source of fluid supply, of a main, a plurality of distributing pipes connected therewith, means including a selector relay for controlling the admission of fluid from the supply source to the main, and means including a valve and a valve-operating selector relay associated with each distributing pipe for controlling the amount of fluid admitted from the main to the distributing pipes.
11. In a fluid circulating system, the combination, with the source of fluid supply, of a main, a plurality of distributing pipes connected therewith, means including a selector relay for controlling the admission of fluid from the supply source to the main, and means including a valve and valve-operating selector relay for controlling the amount of fluid admitted from the main to each distributing pipe, the selector relays being controllable from a single distant position, and means for actuating at the point of control simultaneously with the actuation of each selector relay a corresponding indicator.
12. In a system of the character disclosed, the combination of a supply pipe receiving steam at high pressure a low pressure main connected therewith, a plurality of distributing pipes connected with the main, a valve controlling the admission of steam from

- the supply pipe to the main, means for maintaining on the discharge side of the valve an intermediate pressure dependent upon the quantity of steam flowing through the valve, a motor for operating the valve, means including a pressure device responsive to said intermediate steam pressure for controlling the valve motor and adapted upon a rise of pressure above a predetermined value to start the motor in a direction to close the valve and on a drop of pressure below such predetermined value to start the motor in the reverse direction to open the valve, valves in the distributing pipes controlling the admission of steam from the main to each, and electrically actuated means controllable from a single point for separately rendering the valve motor control means responsive to different values of the intermediate steam pressure and for operating the valve in each distributing pipe.
13. In a system of the character disclosed, the combination of a supply pipe receiving steam at high pressure, a low pressure main connected therewith, a plurality of distributing pipes connected with the main, a valve controlling the admission of steam from the supply pipe to the main, means for maintaining on the discharge side of the valve an intermediate pressure of steam dependent upon the volume of the steam passing through the valve, a motor for operating the valve, means including a pressure device responsive to said intermediate steam pressure for controlling the valve motor, valves in the distributing pipes controlling the admission of steam from the main to each, and electrically actuated means all controllable from a single point for individually effecting an adjustment of the pressure responsive device so that it will respond to different pressures and for operating the valve in each distributing pipe and, simultaneously with each control operation, for actuating at the point of control a corresponding control indicator.
14. In a fluid circulating system, the combination, with a source of fluid supply, of a circulating main, a motor-operated valve controlling the admission of fluid from the supply source to the main, a plurality of distributing pipes connected with the main, subsidiary electromagnetically actuated valves each controlling the admission of fluid from the main to a distributing pipe, and means controllable from a single given point for controlling the valve motor to thereby regulate the amount of fluid admitted to the main and for selectively actuating the subsidiary valves to thereby selectively regulate the amount of fluid admitted from the main to the individual distributing pipes.
15. In a system of the character described, the combination, with a supply pipe, of a main, a plurality of distributing pipes connected with the main, means for controlling the admission of the fluid from the supply pipe to the main, and electrically actuated means controllable from a single point for selectively controlling the amount of the fluid admitted from the main to each distributing pipe.
16. In a system of the character disclosed, the combination, with a supply pipe, of a main, a plurality of distributing pipes connected with the main, means for controlling the admission of the fluid from the supply pipe to the main, and electrically actuated means controllable from a single point for selectively controlling the amount of the fluid admitted from the main to each distributing pipe.
17. In a system of the character disclosed, the combination, with a supply pipe, of a main, a plurality of distributing pipes connected with the main, means controllable electromagnetically from a single point for regulating the amount of the fluid admitted from the supply pipe to the main and for selectively regulating the amount of the fluid admitted from the main to each distributing pipe.
18. In a system of the character described, the combination, with a supply pipe, of a main, a plurality of distributing pipes connected with the main, and means controllable electromagnetically from a single point for selectively regulating the amount of the fluid admitted both from the supply pipe to the main and from the main to each distributing pipe and for actuating simultaneously therewith corresponding regulation indicating devices at the place of control.

WEBSTER TALLMADGE.
